Primary Examiner — Kevin Rudzinski

CLAIM

The ornamental design for display panel or screen with graphical user interface, as shown and described.

DESCRIPTION

FIG. 1 is a front view of the display panel or screen with graphical user interface showing a first embodiment of my new design; and,

FIG. 2 is a front view of a second embodiment thereof. The broken lines in the FIGS. showing the display screen and portions of the graphical user interface are included to show environment and form no part of the claimed design.
